CLAMP FOR BUILDING FORMS

Earl Jack McGough, Costa Mesa, Calif.

Application November 19, 1949, Serial No. 128,432

9 Claims. (Cl. 25—131)

1

This invention relates to an improved clamp for holding building forms, having particular reference to clamps for temporarily locking such structures as the forms used in the pouring and forming of concrete walls.

A principal object of this invention is to provide clamping means by which building forms may be quickly and easily locked in place and as quickly and easily unlocked and separated without wastage of lumber.

Another object of the invention is to provide clamping means capable of holding building forms at a true right angle, as for the corner of a wall, and requiring no special supplementary forms, metallic or wooden, fastened to the building forms; but only the ordinary wales of two-by-four lumber or the like commonly used and available, these wales being unattached to the wall forms as used with this invention and therefore being available for re-use without loss or injury.

Still another object of the invention is to provide clamping means for use in connection with loose-wales, by which wales may be clamped without alignment, thereby saving time and labor in the application of the wales to the contained forms.

The invention possesses other objects and useful advantages which will be pointed out as the following description of a preferred embodiment of the invention proceeds, or which will be apparent from that description considered in connection with the accompanying drawings, in which:

Figure 1 is a perspective view showing a pair of clamping members embodying the principles of this invention, in position to clamp associated pairs of wales at a right angle to support corner forms for a wall;

Figure 2 is a perspective view of one of the clamping members shown in Figure 1;

Figure 3 is a perspective view showing how the clamping members illustrated in Figures 1 and 2 may be used with an associated member, also a part of this invention, to clamp wales which approach a form corner at different levels; and

Figure 4 is a perspective view of the associated clamping member shown in Figure 3.

Having reference now to the details of the drawing, my invention comprises a clamping member 6 having a general resemblance to a conventional anchor in that it has a shank 7 terminating at one end in a cross-arm 8 corresponding to the fluked arms of an anchor and at the other end in a head 9 having an eye 10, and

that it has a cross-arm 11 between the head 9 and the cross-arm 8 corresponding to an anchor stock. However, the cross-arms 8 and 11 lie in one plane as in a conventionalized representation of an anchor, rather than at right angles as is usually the case with the flukes and stock of an actual anchor. The cross-arm 8 is perpendicular to the shank 7 rather than being curved and may be slightly cambered on its inner surface 12, to provide a wedge-shaped holding edge 13, the better to indent and to grip a piece of lumber.

The cross-arm 11 may also be cambered on its side 15 toward the head 9 to provide a relatively narrow holding surface 16, for the same purpose as the edge 13. At the ends of the cross-arm 11 are points 17, swept towards the cross-arm 8 and outwardly beyond the plane of the holding surface in continuation of the cambered side 15.

The head 9 is so formed as to provide a curved surface 18 on the side of the head opposite to the direction of extension of the points 17, this surface encompassing the eye 10 and providing a convex seat upon which a bolt-head of a bolt passing through the eye 10 may rest. It will be understood that the term bolt-head is inclusive of parts of similar bolt-retaining function such as a nut or a washer. The convex seat 18 may conveniently be formed by curving the head 9 so that at the transverse diameter of the eye 10 it is offset from the plane of the shank 7, the end 19 of the head then recurring so as to be offset from the plane of the shank in the opposite direction. The eye 10 opens radially to the convex seat 18 and is elongated in the axial direction of the shank 7 to permit a bolt received therein to assume in relation to the shank 7 an oblique position in which the end 19 holds the bolt substantially in the plane perpendicular to the cross-arms 8 and 11 and limits the degree of obliquity in that plane. The elongation of the eye 10 may take the form of an enlargement of the eye toward the convex seat 18.

The invention also includes a hook member 20 used in cooperation with the clamping member 6 in certain circumstances as will be hereinafter explained. The hook member 20, illustrated in Figures 3 and 4, has an elongated body 21 provided with eyes 22 for receiving and holding a bolt parallel to the body 21. As shown in Figure 4 the eyes 22 may be separate, to reduce weight, but any suitable eye means such as one cylinder of sufficient length for the purpose stated will suffice. A finger 23 extends from the body 21

beyond the eyes 22 and parallel to and offset therefrom so as to provide a space 24 to receive a bar or like object hooked between the finger and a bolt held in the eyes.

In using the clamps 6 to support building forms for pouring concrete walls and like operations, the clamps are used in combination with suitable bolts 25 and wales 26. The wales 26 may be lumber of the size commonly called two-by-four, or similar pieces, and are arranged in pairs. As shown in Figure 1, these pairs of wales will ordinarily be arranged to approach a wall corner at substantially the same level, and in this case a pair of clamps 6 and one bolt 25 will suffice to tension and to align each two opposed pairs of wales. The cross-bar 8 and shank 7 of a clamp is inserted between the two wales of a pair, and the clamp is rotated to bring the cross-arm 8 to bear upon the side of the wales nearest the building forms and the cross-arm 11 to bear against the opposite or outer side of the wales. The dimensions of a clamp 6 will vary with the dimensions of the lumber used for wales, but the shank 7 between the cross-arms 8 and 11 should be sufficiently long to permit the clamp 6 to lie obliquely to the wales with the cross-arms at opposite sides of the wales, and the cross-arm 11 should be sufficiently long to permit the points 17 to grip the upper and lower sides of the wales and thus maintain the wales in spaced relationship. It may be noted that the points 17 may be on either or both of the cross-arms, but for convenience in inserting the cross-arm 8 between the wales, they are preferably only on the cross-arm 11.

With the clamps 6 so placed in relation to the wales 26, a bolt 25 is placed through the eyes 10 of the clamps and is tensioned by a nut 27 and suitable washers 28. Leverage is thus applied to the clamps to force the holding edges 13 and 16 to grip the wales firmly, and the pairs of wales will be tensioned toward each other at the right angle bisected by the perpendicular to the bolt 25. Due to the convex seats 18 upon which the bolt-heads pull, the bolt will assume the desired 45 degree angle to each pair of wales, although the two clamps may have different obliquity with respect to their respective pairs of wales.

In the event that the pairs of wales approach the corner of the wall at different levels, so as to be staggered vertically as shown in Figure 3, a bar 30 is set up at the corner. The clamps 6 are inserted in the wales in the usual manner, and the hooks 20 are hooked upon the bar and tensioned to the clamps by the bolts 25. The elongated bodies of the bolts, extending on the opposite side of the bar 30 from the respective clamps 6, permit the use of the same length of bolt as would be used to connect two clamps. The bar 30 will be held rigidly as a corner brace when the wales are staggered as shown in Figure 3.

With the system of clamps, or of clamps, hooks and a bar, as herein described, it is not necessary to nail the wales to the forms or to corner posts or to each other. Spacer posts, not shown, may be used to offset the wales from the forms which they support, to permit insertion and rotation of the clamps 6, and the forms may be braced on their interior sides in the usual manner. When the bolts 25 are loosened and removed, the exterior system of wales and forms will disintegrate to its constituent parts without further labor.

I wish it to be understood that the specific forms of clamps 6 and hooks 20 herein illustrated and described are to be interpreted only as exam-

ples of the invention, the scope and spirit of the invention being claimed as follows.

I claim:

1. A clamp for building forms having a shank, a cross-member forming a T with said shank, a cross-arm parallel with said cross-member and having end-points directed substantially at right angles to the plane inclusive of said cross-member and said cross-arm, and a head extending from said shank beyond said cross-arm and curving convexly in the direction opposite to said end-points and having an eye radial to the curvature of said head and enlarging toward the convex side of said head.

2. A clamp for building forms having a shank, a cross-member forming a T with said shank, a cross-arm parallel with said cross-member and having end-points directed substantially at right angles to the plane inclusive of said cross-member and said cross-arm, and a head extending from said shank beyond said cross-arm and having an eye for receiving a bolt or the like, the surface of said head on the side thereof opposite to said end-points being convex and said eye being radial to said convex surface.

3. A clamp for building forms having a shank and parallel cross arms on said shank, said shank being adapted to be inserted between two of said forms, said cross-arms engaging said two forms on opposite sides when said shank is turned at a right angle from its position during insertion, points on one of said cross-arms for engaging the outer sides of said form to hold said form in spaced relationship, and a head portion extending beyond one of said cross-arms and having an eye axially normal to said cross-arms for receiving a bolt or the like and having a curved surface forming a convex seat for a bolt-head.

4. In clamping mechanism for building forms, in combination with opposed pairs of wales arranged to hold said forms so as to define a corner: clamps individual to each of said pairs, each of said clamps having a shank portion adapted to be inserted between the wales of the pair respective to said clamp, and having spaced cross-arms adapted to engage opposite sides of said wales when said shanks have been so inserted and then rotated, and having angulated points on the ends of one of said cross-arms for then engaging the outer sides of said wales to prevent spreading of said wales, said cross-arms being spaced apart a distance greater than the width of said wales whereby said clamp may be disposed at an angle to said wales, and a head in extension of said shank having an eye therein; and bolt means engageable in said eyes for drawing the clamps of opposed pairs of wales convergently, and pivotally upon said cross-arms; said heads having curved surfaces providing convex seats whereon said bolt means may pivot to assume angular relationship to said clamps varying with the angular relationship of said clamps to said wales.

5. In clamping mechanism for building forms, in combination with staggered pairs of wales arranged to hold said forms so as to define a corner: clamps individual to each of said pairs, each of said clamps having a shank portion adapted to be inserted between the wales of the pair respective to said clamp, and having spaced cross-arms adapted to engage opposite sides of said wales when said shanks have been so inserted and then rotated, and having angulated points on the ends of one of said cross-arms for then engaging the outer sides of said wales to prevent spreading of said wales, said cross-arms

being spaced apart a distance greater than the width of said wales whereby said clamp may be disposed at an angle to said wales, and a head in extension of said shank having an eye therein; a bar; hook means engageable with said bar in opposition to each of said clamps and having eyes for receiving a bolt; and bolt means respective to each of said clamps and the hook means opposed thereto and engageable in the eyes thereof to tension said clamps toward said bar.

6. In mechanism for clamping associated parallel wales for the support of building forms, the combination of: a bolt; a bar; a hook having a finger for engaging said bar and eye-means receptive to said bolt and adapted to hold said bolt parallel to said finger; and a clamping member having a shank and parallel cross-arms on said shank so spaced that when said cross-arms engage opposite sides of said wales said shank may lie obliquely to said wales, and having a head in extension of said shank beyond one of said cross-arms and an eye in said head receptive to said bolt and elongated to permit said bolt to lie obliquely to said shank.

7. In mechanism for clamping associated parallel wales for the support of building forms, the combination of: a clamp having a shank for insertion between two of said wales, a first cross-member forming a T with said shank for engaging one side of said two wales, a second cross-member parallel with said first cross-member for engaging the opposite sides of said two wales, one of said cross-members having end-points directed substantially at right angles to the plane inclusive of said cross members, and a head extending from said shank beyond said second cross-member and having an eye, the surface of said head on the side thereof opposite to said end-points being convex and said eye being radial to said convex surface; and bolt means including a member passing through said eye having retaining means at one end seated on said convex surface and means at the other end for drawing said retaining means against said convex surface, thereby to hold said member in angular relationship to said clamp varying with the angular relationship of said clamp to said wales.

8. In mechanism for clamping wales associated in pairs and arranged to support building forms

so as to define a corner: clamps individual to each of said pairs, each of said clamps having a shank portion adapted to be inserted between the wales of the pair respective to said clamp, and having spaced cross-arms adapted to engage opposite sides of said wales when said shanks have been so inserted and then rotated, and having angulated points on the ends of one of said cross-arms for then engaging the outer sides 10 of said wales to prevent spreading of said wales, said cross-arms being spaced apart a distance greater than the width of said wales whereby said clamp may be disposed at an angle to said wales; and a head in extension of said shank having an 15 eye therein and a convex surface surrounding said eye on the side of said head opposite to said points; and means for drawing toward said corner the clamps of pairs of wales defining opposite sides of said corner, inclusive of means 20 passing through said eyes and pivoted on said convex surfaces.

9. A clamp for building forms having a shank and parallel cross arms on said shank, said shank being adapted to be inserted between two of said 25 forms, said cross-arms engaging said two forms on opposite sides when said shank is turned at a right angle from its position during insertion, points on one of said cross arms for engaging the outer sides of said forms to hold said forms in 30 spaced relationship, and a head portion extending beyond one of said cross arms and having an eye axially normal to said cross arms for receiving a bolt or the like, said eye being elongated in the axial direction of said shank to permit said 35 bolt to be angulated with respect to said shank in a plane normal to the plane of said cross-arms and parallel to said shank.

EARL JACK McGOUGH.
